DISTILLATION UNIT

John C. Cleaver and Jules Verne Resek, Whitefish Bay, Wis., assignors to Cleaver-Brooks Company, Milwaukee, Wis., a corporation of Wisconsin

Application June 10, 1942, Serial No. 446,482

5 Claims. (Cl. 202—174)

This invention relates to a water distillation unit and has as a general object to provide a new and improved, highly efficient distillation unit.

A more particular object of the invention is to provide a new and improved distillation unit having a plurality of effects or evaporators, with the evaporators after the first having a heat exchanger constituting the heating means for the evaporator and the condensing means for the steam of the previous evaporator.

Another object is to provide a new and improved distillation unit for operation on salt water and embodying means for driving off gases from the water before it is vaporized.

Another object is to provide a distillation unit having an aerator for aerating water ultimately to become distillate, at a temperature near boiling where odors and gases are readily given off.

Yet another object is to provide a distillation unit having evaporating means and means permitting a continuous blow-down from the evaporating means to prevent the water in the evaporating means from obtaining an excessively high salt content.

A further object is to provide a distillation unit having a plurality of effects or evaporators with a pump for supplying water to the first effect at a rate in excess of the evaporation in the unit, a continuous blow-down from the first evaporator to the other evaporators at a rate in excess of the evaporation of said other evaporators and blow-downs from the other evaporators.

Yet another object is to provide a distillation unit, having an evaporator, a condenser and an aerator, means connected to the condenser at a point spaced from the end thereof to conduct to waste a portion of the coolant water flowing therethrough, a means connected to conduct the coolant water flowing completely through the condenser to the aerator.

Still a further object is to provide in a distillation unit a first effect evaporator or boiler with a multiple pass, large diameter fire tube withdrawable through the end of the boiler for cleaning.

Other objects and advantages will become apparent from the following detailed description, taken in connection with the accompanying drawings, in which:

Fig. 1 is a perspective view of a device embodying the features of our invention. Casing portions are cut away in the view in order to reveal certain interior constructions.

Fig. 2 is an enlarged plan view of one element of the distillation unit, namely, the aerator.

Fig. 3 is a sectional view taken approximately along the line 3—3 of Fig. 2.

Fig. 4 is a sectional view taken approximately along the line 4—4 of Fig. 2.

Fig. 5 is a diagrammatic view showing the circuit arrangement of the distillation unit, with dotted, broken and solid arrows indicating the presence and direction of flow of vapor, condensate and coolant, respectively.

Fig. 6 is a plan view, again with certain casing portions broken away to reveal the interior, of the right half of the distillation unit shown in Fig. 1.

Fig. 7 is a side elevational view of the construction shown in Fig. 6, again with a portion of the casing broken away to reveal the interior.

Fig. 8 is a side elevational view showing the heating tubes partially withdrawn for purposes of cleaning.

While the invention is susceptible of various modifications and alternative constructions, it is here shown in the drawings and will hereinafter be described in the preferred embodiment showing a two effect distillation unit. It is not intended, however, that the invention is to be limited thereby to the two effect units since features thereof are readily applicable to units having more than two effects. The scope of the invention is defined in the appended claims.

In the embodiment disclosed herein, the invention comprises generally a first effect evaporating means, generally designated 10, a second effect evaporating means, generally designated 11, an aerator, generally designated 12, a condenser, generally designated 13, and a cooler, generally designated 14. These various subassemblies are combined into a unit assembly mounted upon an elongated frame 15 with the first and second evaporating means supported directly on the frame 15 in end to end relationship, and with the remaining subassemblies disposed at the remaining end of the second evaporating means and supported either by the evaporating means or directly by the frame 15. As disclosed in Fig. 1, for exemplary purposes, the frame 15 is in turn supported upon a wheeled undercarriage structure, generally designated 16, shown in broken lines. While the distillation unit is admirably adapted, and is in fact intended, to be employed as a portable unit for use in the field, it is to be understood, of course, that it might equally well be stationarily mounted.

For a more ready understanding of the invention, as the structures making up the distillation unit are described in detail, the operation of the

unit will be set forth generally. Heat is supplied to the first effect evaporating means 10 from a primary heat source and causes the water in the first evaporating means to form steam and vapor. It is a feature of this invention that this steam or vapor is herein utilized to provide the heat for evaporating the water in the second effect evaporating means. To that end, it is conducted to a heat exchanger, located in the second evaporating means, which functions both as a heat source for the second evaporating means and as a condenser for the steam and vapor obtained from the first evaporating means. The condensate resulting is conducted to the condenser 13 and from there to the cooler 14 to flow from the latter as cooled distillate. The vapor of the second effect evaporating means is conducted to the top of the condenser 13 to be thereby condensed into condensate, which, like the condensate from the heat exchanger, flows through the cooler 14 to issue therefrom as cooled distillate. Coolant water is initially supplied to the cooler 14 and, after flowing through the cooler 14 is conducted to the condenser 13 from whence a large portion of the coolant water is discharged to waste. A portion of the coolant which, as a result of its passage through the cooler and the condenser, has been heated to near the boiling point is discharged to the aerator 12 where it has an opportunity to give off undesirable fumes and odors. From the aerated water there is drawn the water supplied to the evaporating means to be by the process just described converted into pure, cooled distillate.

The subassemblies will now be described in greater particularity, and the first effect evaporating means 10 will be first considered. This first effect evaporating means is in reality a boiler composed of a cylindrical casing or shell 11 and suitable heat exchange means 18. The inner end 19 of the boiler, as viewed in Fig. 1, is integrally and permanently attached to the cylindrical side walls of the boiler, while the opposite or outer end of the boiler is formed by a removable, circular head 20. The head 20 is removably secured by means of a plurality of bolts 21 extending through the head at its periphery and through an external, annular flange 22 formed on the shell 17. The head 20 in turn is formed with a man hole 23 (see Figs. 6 to 8) through which access may be had to the interior of the boiler for inspection and minor repair or cleaning without necessity of removing the entire head.

The heat exchange means 18 herein employed is of unique construction and comprises a fire tube 25 of comparatively large and uniform diameter throughout its length. The fire tube 25 at one end is rigid with the head 20 at a point adjacent the periphery and just below the horizontal diameter of the head, at which point the head is formed with an opening 26 for the discharge into the tube of a combustible mixture. From this point, the fire tube extends longitudinally toward the opposite end of the boiler and is then bent upon itself numerous times to form four passes disposed in the same horizontal plane. From the last pass, the tube extends first laterally of the boiler toward the first pass, then downwardly and again laterally, to commence a second horizontal layer of four passes lying beneath the first layer. The remaining end of the fire tube is, like the first end, rigid with the head 20 and opens to a flue 27 formed on the exterior of the head 20. Although the fire tube 25 is

herein illustrated as of the same diameter throughout its length, the first portion or pass may be in some instances larger in diameter to form a larger combustion chamber. In either event the entire tube 25 is withdrawable from the shell 17 as an incident to removal of the head 20 giving complete access to the fire tube for cleaning scale therefrom or for inspection or repair.

10 The boiler herein is fired by means of an oil burner of conventional type. Suffice it to say, therefore, that the burner comprises a nozzle 30 (see Fig. 1), a fuel oil pump 31 (see Figs. 6 and 7) supplying fuel oil to the nozzle, and a blower 32 supplying both primary air for atomization of the fuel as it is discharged from the nozzle 30 and secondary air for supporting combustion. The blower and nozzle are supported directly on the head 20 with the nozzle 30 projecting into the opening 26, while the fuel oil pump 31 is supported on a plate 33 removably secured by bolts 34 on the frame 15. Driving the blower and the fuel oil pump 31 is a power unit 35, preferably a gasoline engine, also mounted on the plate 33. Projecting from the power unit is a shaft 36 having non-rotatably secured thereon a plurality of pulleys 37 and a single smaller diameter pulley 38. The smaller pulley 38, through a belt 39, drives the fuel oil pump 31, while one of the larger pulleys 37, through a belt 40, drives the blower 32. Removal of the head 20 and withdrawal of the fire tube 25 for cleaning or repair, as previously described, is, of course, impossible without removal of the power unit 35, the fuel oil pump 31, and other structures, which will hereinafter be described. It is therefore of importance in this invention that the plate 33 is removably secured, enabling the plate 33 and the parts mounted thereon to be removed, if desired, simultaneously with the removal of the head 20.

35 The secondary effect evaporating means is distinctly an evaporator and comprises a casing 42, generally rectangular in horizontal cross section, and having a rounded top. Each side wall of the casing 42 is composed in part of a door 43 hinged-45ly supported at 44 and adapted to be tightly closed to prevent leakage of the water in the evaporator. Supported internally on each of the doors 43 is a heat exchanger, generally designated 45, and herein shown as composed of a plurality of coils 46. Physically one of the heat exchangers 45 is shown in the drawings, but in the diagrammatic view of the circuit the other heat exchanger and the coils composing the same is diagrammatically shown at 47.

50 Disposed above the normal water level in the casing 42 are a plurality of baffles 48 and 49 projecting inwardly and partially across the evaporator from opposite end walls. At the very top of the second evaporating means is an enlarged tube 50 open at one end to the interior of the evaporating means and discharging at the other end through a conduit 51 of somewhat smaller diameter to the top of a downwardly extending and diverging header 52 opening at its lower end to the top of the condenser 13. It is believed apparent from the foregoing that improved efficiency of operation is obtained by the employment of a heat exchanger in the second effect which serves to condense the steam or vapor from the first effect and thereby utilize the heat which is present in such steam or vapor.

55 Herein the condenser 13 is shown as supported from the end of the casing 42 of the second effect.

The condenser is of conventional construction, being composed, as clearly seen in Fig. 1, of a plurality of tubes 53 supported at their ends in heads 54. The tubes are in well known manner arranged in groups and discharge to chambers formed by baffles 55 interposed between each head 54 and a recessed closure plate 56. The arrangement of the baffles is such that coolant flows through one set of tubes, thence laterally to another set of tubes, thence through the tubes and upwardly to the set of tubes above, and thence through the tubes and again laterally to another set of tubes longitudinally and upwardly as before. The vapor passes over the exterior of the tubes 53 and thus is condensed by the coolant 15 as the temperature of the latter is raised.

The cooler 14 also is of conventional construction with the specific structure forming no part of this invention. Suffice it to say, therefore, that here again the cooler is composed of a plurality of tubes 57 terminating in heads 58. Interposed between the heads 58 and end closures 59 are baffles 60 to direct coolant water supplied to the cooler from end to end successively through different groups of tubes. The condensate to be 25 cooled flows over and around the tubes 57 to issue as cool, clear distillate.

Referring now particularly to Figs. 2 to 4, the aerator 12 shown therein comprises a generally rectangular container having a bottom wall 65 resting upon or even formed by the top wall of the condenser 13, and end and side walls 66, 67, 68 and 69. Extending downwardly through the container and interrupting the continuity of the inner surface of the side wall 69 is the header 52. 30 No top wall is provided for the container in order that it may be open to atmosphere for the discharge to atmosphere of any odors in the water discharged to the aerator. The side walls 68 and 69 may be formed as continuations of the corresponding walls of the condenser 13.

The container is divided into numerous chambers or compartments by means of a plurality of partitions. One such partition 70 extends from end wall 66 to end wall 67, and at its upper edge is flush with the upper edges of the end walls. Over more than half its length, however, the partition is cut away near the bottom wall 65 so as to provide at the bottom of the partition an elongated opening 71. Extending transversely of the container between the side wall 69 and the fuel portion of the partition 70 is a second partition 72 spaced a short distance from the end wall 66. This partition extends to the bottom wall 65, but is only about half as high as the peripheral walls of the container. A third partition 73 also extends transversely of the container between side wall 69 and the partition 70. This partition extends to the bottom wall 65 of the container and is flush with the top edge of the peripheral walls. It is spaced from the end wall 66 a distance approximately twice the spacing of the partition 72. Division of the container into chambers is completed by a fourth partition 74 which extends longitudinally of the container between the end wall 67 and the partition 73. This partition is comparatively close to the partition 70 and extends to the bottom wall 65, but terminates somewhat short of the upper edge of the peripheral walls and hence of the upper edge of the partitions 70 and 73. It is believed apparent that the four partitions divide the container into five chambers or compartments designated in the order of their formation in the above description, respectively, 76, 77, 78, 79 and 80.

Formed in the partition 70 adjacent the end wall 66 is a V-shaped notch 82, the apex of which is disposed just slightly below the upper edge of the partition 74. The purpose of this notch so located with its apex below the level of the upper edge of the partition 74 is to permit any scum that may form on the surface of the water in the compartment 76 to flow off into compartment 77 which is the waste flow-off compartment, being formed with a discharge opening 83 in the bottom of the side wall 69. A V-shaped notch 84 similar to the notch 82 is also formed in the partition 73. The apex of this notch is below the top edge of the partition 74, permitting excess water in the compartment 79 to flow into compartment 78 and thence over partition 72 into compartment 71. Near its lower edge, the partition 73 is formed with an opening, and inserted in this opening to control the flow of water therethrough is a check valve 85. This valve is disposed to prevent flow of water from the compartment 78 to the compartment 79, but to permit flow in the reverse direction. It is for the purpose of constantly maintaining in the compartment 78 a reserve supply of water that may flow into the compartment 79, should the water therein fall below a desired level, that the partition 72 is provided. This partition extends well above the check valve controlled opening in the partition 73 and thus maintains a reserve of water with a head sufficient to open the check valve 85 and discharge to the compartment 79 should the water in that compartment drop below a desired level.

It is to be understood that the aerator is constantly supplied with an excess quantity of water. As a matter of fact, it is a feature of this invention that excess quantities of water are supplied to all of the parts of the distillation unit. This will best be understood from a consideration of the fluid system of the distillation unit which will now be described. This system is best understood from the diagrammatic showing thereof in Fig. 5, and reference will primarily be made to that figure. However, for the most part, that system is also shown as it actually is constructed in some one or other of the remaining figures, and where possible the actual construction thus shown will be identified by the same reference character applied to the diagrammatic showing of Fig. 5. For convenience, the system will be described in the order of the flow of water from its source, which may be a creek, a lake, or any other natural accumulation, to its discharge from the unit as potable, clear, and germ-free distillate.

Initiating such a system is an intake conduit 90 leading to a pump 91, which will hereinafter be termed the cold water pump. This pump, as clearly seen in Figs. 1, and 6 to 8, is mounted on the plate 88 so as to be removable therewith, and is driven from the engine 35 by a belt 92 running over one of the pulleys 37. In Figs. 1 and 6 to 8, the conduit 90 is shown short and capped. It is understood, of course, the distillation unit will carry adequate conduit means, usually hosing, which will be attached to the conduit 90 to form an extension thereof. In fact it may in some instances even prove desirable to carry a booster pump to lift the water from the source to approximately the level of the pump 91. Leading from the discharge side of the pump 91 is a conduit 93 opening through the closure 59 of the cooler 14 to discharge to an appropriate chamber formed by the baffle 60 between the closure and

the head 58. Interposed in this conduit 93 to control the flow of water therethrough is a valve 94. The water thus supplied through the conduit 93 acting as a coolant flows through the tubes 57 and thence through a conduit 95 leading from the closure 59 to the closure plate 56 of the condenser 13, and to the lowermost of the chambers formed by the baffles 55 between the head 54 and the closure plate 56. The water or coolant, thus partially heated by the heat subtracted from the condensate in the cooler, flows through the tubes 53 of the condenser 13, as previously described.

Tapped into the condenser at a point short of the upper terminus thereof, as best seen in Fig. 5, is a conduit 96 designed and proportioned to take off and discharge directly to waste a portion of the water flowing through the cooler and condenser, and serving as a coolant. This conduit 96, clearly shown in Fig. 3, extends from the condenser upwardly and partially over the aerator 12 to terminate approximately over the compartment 78. The conduit 96 is closed at its end by a cap 97 but is cut away at 98 on its underneath side to discharge downwardly into the compartment 78 of the aerator. Leading from the upper and final terminus of the condenser is a conduit 99. This conduit, as best seen in Figs. 2 and 3, also extends upwardly and laterally to project over the aerator 12. This conduit is disposed over the compartment 16 and extends over substantially the full length of the compartment and throughout its horizontal portion has its top half cut away to form a trough 100. It will be noted that the water discharged to the compartment 16 passes through the final, uppermost tubes of the condenser not reached by the water discharged through the conduit 96. This water is thus raised to a higher temperature and preferably the distillation unit should be so operated that the temperature of this water is raised approximately to the boiling point, while the water discharged through the conduit 96 has a temperature of from 180° to 200° Fahrenheit.

The water discharged through the conduit 96 to the compartment 16 will overflow the compartment and discharge over the top of the partition 72 to the compartment 11. From there it will flow through the opening 83 through a waste conduit 103 threaded into the opening 83. The water discharged through conduit 99 to compartment 16 will in the main flow underneath the partition 70 into the compartment 80 and thence over the upper edge of the partition 74 to the compartment 79. A smaller quantity will, as previously described, flow through the notch 82 so as to skim off any scum that may form on the top of the compartment 76. With proper operation, an excess quantity of water will be supplied to the compartment 79 and will flow off through the notch 84. However, should this excess temporarily be absent, a certain level of water will be maintained in the compartment 79 by reason of the constant and excessive supply of water discharged through conduit 96 to the compartment 11.

The heated and aerated water in the compartment 79 is utilized as the feed water for the first effect evaporating means 10. To that end, a conduit 104 opens at one end through the side wall 69 of the aerator (see Fig. 2) and connects with the intake of a pump 105 which, to differentiate from the pump 91, will hereinafter be called the hot water pump. This pump (see Figs. 6 to 8) is mounted on the plate 33 to be removable therewith, and is driven by a belt 106 running

over the remaining one of the pulleys 37. Leading from the discharge port of the pump 105 is a conduit 107 discharging at the other end to the first effect evaporating means 10. Interposed in this conduit 107 is a valve 108 to control the quantity of water discharged to the first effect evaporating means. In order that the water in the first effect evaporating means, especially if sea water is being distilled, may not attain too high a salt concentration, or for that matter a concentration of any other substance that is not evaporated, means is provided for effecting a continuous change in the water in the first effect evaporating means. To that end, feed water is supplied to the first evaporating means in quantities substantially in excess of the amounts evaporated. The amount of excess varies with the condition of the water being distilled, but for average conditions the excess supplied is from seventy-five per cent to one hundred per cent of the amount of the distillate.

With provision made to supply feed water in excess of the rate of evaporation, means is also provided for a discharge from the first effect evaporating means of the excess feed water supplied. Herein this supply and exhaust of excessive feed water is utilized not only to provide for continuous change in the water of the first effect evaporating means, but to supply and, in fact, again continuously change the feed water for the second effect evaporating means. To that end, provision is made to have the first effect evaporating means blown-down to the second effect evaporating means. Consequently, there is connected between the boiler of the first effect evaporating means and the second effect evaporating means a conduit 109 having interposed therein a valve 110 for controlling the rate or quantity of blow-down. This rate of blow-down should, of course, be enough to keep the water in the first effect evaporating means at a constant, proper level, and at the same time supply to the second effect evaporating means feed water at a rate in excess of the evaporation from the second effect evaporating means. The excess is discharged from the second effect evaporating means through a conduit 111 leading to waste. This conduit contains no valve and for proper operation there should be a continuous discharge from this conduit. Conduit 109 is, of course, connected to boiler 17 at a point below the normal water level so as to always be covered with water, while conduit 111 is connected just at the normal water level of the second evaporating means.

The steam that is generated in the first effect evaporating means is, by a pair of conduits 112 and 113 opening to the boiler 17 near the top thereof through the end 18, led to the heat exchangers 47 and 45, respectively. In passing through the plurality of coils forming each of the heat exchangers 45 and 47, the steam is condensed and the condensate is by the steam pressure in the coils forced through the conduits 114 and 115, connected respectively to the heat exchangers 47 and 45, to the bottom of the condenser 13. To regulate the flow of condensate there is interposed in the conduit 114 a valve 116, and in the conduit 115 a valve 111. These should be so adjusted that only condensate flows through the conduits, and not uncondensed, live steam. The heat given off by the steam in condensing operates through the heat exchangers 45 and 47 to evaporate the water in the second effect evaporating means. This vapor then flows through the tube 50 and conduit 51 to the header

52 and thence downwardly through the header and over the tubes 53 of the condenser 13, where the vapor is condensed into condensate. This condensate joins with the condensate received from the heat exchangers 45 and 47 and flows from the condenser through a conduit 118 that leads from the bottom of the condenser to the top side of the cooler 14 where the condensate is further cooled by contact with the tubes 51. Finally there leads from the cooler a conduit 119, suitably capped or valved, through which the final distillate may be withdrawn for use.

Provision is, of course, made for the initial filling of the boiler and the casing 42 to the proper level, as well as for the draining of the boiler, the casing 42, the heat exchangers 47 and 45, the condenser, and the cooler. All or parts of the conduits or valves for those purposes are shown in Fig. 1, but have not been incorporated in the diagrammatic showing of Fig. 5, inasmuch as they are more or less conventional and form no part of this invention. No detailed description thereof has therefore been made.

Where the distillation unit is mounted upon a wheeled undercarriage structure, so as to be portable, one or more tanks 120 may be supported beneath the frame 15 for carrying the fuel oil and the gasoline necessary to operate the oil burner and the motor 35.

It is believed apparent from the foregoing that we have perfected a unique and vastly improved distillation unit, and especially one that is particularly well adapted for use in the field where it is called upon to distill the worst types of water, and many times sea water with its initial high salt content. With our distillation unit, an excessively high salt content in either evaporating means is prevented by the continuous change of the water in the evaporating means. Moreover, not only does this feature contribute to an ultimately potable distillate, but an odor-free distillate is further assured by the provision for aerating all of the water that is ultimately converted into distillate. This aeration as herein effected is performed with the water at a high temperature where the odors are most easily taken off.

In the past great difficulty has been experienced when distilling salt water because of the foaming which occurs when the water is heated in the first effect of the still. In our apparatus the gases which are formed or liberated in impure or salt water when it is heated, are driven off in the aerator with the result that foaming is substantially eliminated in the evaporators.

Our construction also provides for ready access to the heating means or heat exchangers of both evaporating means. Any scale which accumulates may thus be easily and thoroughly removed, assuring the most efficient operation of the evaporating means at all times. Increased efficiency is also assured by the employment, first, of the heated coolant water of the cooler and the condenser for feed water of the first evaporating means, secondly, of the heated water of the first evaporating means as the feed water for the second evaporating means, and, thirdly, of the steam of the first evaporating means as the heat for evaporating the water of the second evaporating means. Other features and advantages, it is believed, are clearly apparent from the objects and the detailed description of the invention.

We claim as our invention:

1. A distillation unit comprising, in combination, a first evaporator comprising a casing and fire tubes within the casing, a second evaporator comprising a casing and heat exchanger means within the casing, a first conduit leading from a point near the top of the casing of the first evaporator to the heat exchanger means of the second evaporator, a second conduit leading from the casing of the first evaporator at a point below the normal water level thereof to the casing of the second evaporator, a valve means interposed in said second conduit open during the operation of the distillation unit to permit a continuous flow of water from the first evaporator to the second evaporator at a rate in excess of the rate of evaporation therefrom, a conduit discharging to waste opening to said second evaporator at about the normal water level therein, a condenser, means for conducting the vapor of said second evaporator to said condenser, a cooler, means for conducting the condensate from the condenser and the condensate from said heat exchanger to said cooler, an aerator, means for supplying coolant water to said cooler and to said condenser, means discharging a portion of the coolant water to the aerator, and means for drawing water from said aerator and discharging the same continuously to said first evaporator at a rate in excess of the rate of evaporation of both evaporators.
2. A distillation unit comprising a first evaporator, a second evaporator, means for continuously supplying water to the first evaporator at a rate of from 75% to 100% in excess of the rate of distillate production from both evaporators, a conduit connected at one end to the first evaporator at a point below the normal water level thereof and at the other end to the second evaporator, a valve in said conduit normally adjusted to permit a continuous flow of water from the first evaporator to the second evaporator at a rate in excess of the rate of evaporation from the second evaporator and to maintain a predetermined water level in said first evaporator, and a normally open conduit connected to the second evaporator at about the normal water level thereof for the continuous discharge therethrough of the excess water supplied to the second evaporator.
3. A distillation unit comprising, in combination, evaporating means, an upright condenser having a plurality of horizontally disposed tubes interconnected for the passage of coolant water laterally and progressively upwardly, a cooler having a plurality of tubes for the passage of coolant water laterally and progressively upwardly, a conduit drawing vapor from the evaporating means and discharging the same to the top of the condenser for downward flow of the vapor and distillate over the tubes of the condenser, and means for supplying aerated and heated water to the evaporating means including a pump operable to draw water from a source and discharge the same to the cooler at a rate greatly in excess of the feed water requirements of the evaporating means, a conduit leading from the cooler and discharging to the lowermost tubes of the condenser for flow of the coolant water progressively upwardly through the tubes of the condenser counter to the direction of flow of vapor and distillate in the condenser, a conduit tapped into the coolant water circuit of the condenser at a point in advance of the end thereof for the discharge to waste of a major portion of the

coolant permitting a reduced quantity of coolant to pass through the remaining tubes of the condenser to be heated to a temperature just short of boiling, a conduit tapped into the coolant water circuit of the condenser at the end thereof, an aerator to which the last named conduit discharges at a rate in excess of the feed water requirements of the evaporating means, a conduit leading from the aerator to the evaporating means, a pump interposed therein and operable continuously to supply heated and aerated feed water to the evaporating means at a rate of 75% to 100% in excess of the evaporation requirements of the evaporating means, and means for permitting a continuous blow-down of the evaporating means.

4. A distillation unit comprising, in combination, evaporating means, a water cooled condenser to which vapor from the evaporating means is conducted to be condensed into distillate, a water-operated cooler connected to said condenser to receive the distillate therefrom, and means for supplying aerated and heated water to said evaporating means including a pump operable to draw water from a source and discharge the same to said cooler at a rate greatly in excess of the feed water requirements of said evaporating means, a conduit leading from said cooler to said condenser for conducting the partially heated water to said condenser for further absorption of heat while reducing the vapor in the condenser to distillate, an aerator having a first, a second and a third compartment, with the second and third compartments operable to maintain a reserve of liquid, a conduit tapped into the coolant water circuit of said condenser at a point in advance of the end thereof and discharging to the second compartment of said aerator and designed to take off the major part of the coolant flowing through said condenser, a conduit tapped into the coolant water circuit of said condenser at the end thereof and discharging to the third compartment of said aerator, the rate of discharge being in excess of the feed water requirements of said evaporating means, said third compartment overflowing into the first compartment and said second compartment providing a reserve operable to flow into said first compartment if the overflow from said second compartment is insufficient to maintain the water in the first compartment at a predetermined level, a feed water conduit leading from the bottom of said first compartment to said evaporating means, a pump in said conduit continuously supplying feed water to said evaporating means at a rate in excess of the evaporation thereof, and means for permitting a continuous blow-down from said evaporating means.

5. A distillation unit comprising, in combina-

tion, a first evaporator comprising a casing and fire tubes within the casing, a second evaporator comprising a casing and heat exchanger means in the form of upright coils within the casing, a first conduit leading from a point near the top of the casing of the first evaporator to the top of the heat exchanger means of the second evaporator, a second conduit leading from the casing of the first evaporator at a point below the normal water level thereof to the casing of the second evaporator, valve means interposed in said second conduit open during the operation of the distillation unit to permit a continuous flow of water from the first evaporator to the second evaporator, a conduit discharging to waste opening to the casing of the second evaporator at about the normal water level of the casing, an upright condenser having a plurality of horizontally disposed tubes interconnected for the passage of coolant water laterally and progressively upwardly, a cooler having a plurality of tubes for the passage of coolant water laterally and progressively upwardly, a conduit leading from the top of the casing of the second evaporator and discharging vapor to the top of the condenser for downward flow over the tubes of the condenser, a conduit leading from the bottom of the heat exchanger coils of the second evaporator to the bottom of the condenser, a common conduit leading from the bottom of the condenser to the cooler for flow of the distillate over the tubes of the cooler, and means for supplying aerated and preheated feed water to the first evaporator comprising a coolant pump operable to draw water from a source and discharge the same to the tubes of the cooler at a rate many times in excess of the feed water requirements of the evaporators, a conduit leading from the cooler and discharging to the lowermost tubes of the condenser for flow of the coolant water progressively upwardly through the tubes of the condenser counter to the direction of flow of vapor and distillate in the condenser, a conduit tapped into the coolant water circuit of the condenser at a point in advance of the end thereof, a second conduit tapped into the coolant water circuit of the condenser at the end thereof with the flow of water through the last named first and second conduits being proportioned so that the water flowing through said last named second conduit is raised to a temperature just short of boiling, an aerator to which said last named second conduit discharges, and means including a pump for drawing water from said aerator and continuously supplying the same to the first evaporator at a rate of 75% to 100% in excess of the evaporation requirements of both evaporators.

JOHN C. CLEAVER.
JULES VERNE RESEK.

DISCLAIMER

2,388,599.—John C. Cleaver and Jules Verne Resek, Whitefish Bay, Wis. DISTILLATION UNIT. Patent dated Nov. 6, 1945. Disclaimer filed Aug. 28, 1946, by the assignee, Cleaver-Brooks Company.

Hereby enters this disclaimer to claim 4 of said Letters Patent.

[Official Gazette October 1, 1946.]

coolant permitting a reduced quantity of coolant to pass through the remaining tubes of the condenser to be heated to a temperature just short of boiling, a conduit tapped into the coolant water circuit of the condenser at the end thereof, an aerator to which the last named conduit discharges at a rate in excess of the feed water requirements of the evaporating means, a conduit leading from the aerator to the evaporating means, a pump interposed therein and operable continuously to supply heated and aerated feed water to the evaporating means at a rate of 75% to 100% in excess of the evaporation requirements of the evaporating means, and means for permitting a continuous blow-down of the evaporating means.

4. A distillation unit comprising, in combination, evaporating means, a water cooled condenser to which vapor from the evaporating means is conducted to be condensed into distillate, a water-operated cooler connected to said condenser to receive the distillate therefrom, and means for supplying aerated and heated water to said evaporating means including a pump operable to draw water from a source and discharge the same to said cooler at a rate greatly in excess of the feed water requirements of said evaporating means, a conduit leading from said cooler to said condenser for conducting the partially heated water to said condenser for further absorption of heat while reducing the vapor in the condenser to distillate, an aerator having a first, a second and a third compartment, with the second and third compartments operable to maintain a reserve of liquid, a conduit tapped into the coolant water circuit of said condenser at a point in advance of the end thereof and discharging to the second compartment of said aerator and designed to take off the major part of the coolant flowing through said condenser, a conduit tapped into the coolant water circuit of said condenser at the end thereof and discharging to the third compartment of said aerator, the rate of discharge being in excess of the feed water requirements of said evaporating means, said third compartment overflowing into the first compartment and said second compartment providing a reserve operable to flow into said first compartment if the overflow from said second compartment is insufficient to maintain the water in the first compartment at a predetermined level, a feed water conduit leading from the bottom of said first compartment to said evaporating means, a pump in said conduit continuously supplying feed water to said evaporating means at a rate in excess of the evaporation thereof, and means for permitting a continuous blow-down from said evaporating means.

5. A distillation unit comprising, in combina-

tion, a first evaporator comprising a casing and fire tubes within the casing, a second evaporator comprising a casing and heat exchanger means in the form of upright coils within the casing, a first conduit leading from a point near the top of the casing of the first evaporator to the top of the heat exchanger means of the second evaporator, a second conduit leading from the casing of the first evaporator at a point below the normal water level thereof to the casing of the second evaporator, valve means interposed in said second conduit open during the operation of the distillation unit to permit a continuous flow of water from the first evaporator to the second evaporator, a conduit discharging to waste opening to the casing of the second evaporator at about the normal water level of the casing, an upright condenser having a plurality of horizontally disposed tubes interconnected for the passage of coolant water laterally and progressively upwardly, a cooler having a plurality of tubes for the passage of coolant water laterally and progressively upwardly, a conduit leading from the top of the casing of the second evaporator and discharging vapor to the top of the condenser for downward flow over the tubes of the condenser, a conduit leading from the bottom of the heat exchanger coils of the second evaporator to the bottom of the condenser, a common conduit leading from the bottom of the condenser to the cooler for flow of the distillate over the tubes of the cooler, and means for supplying aerated and preheated feed water to the first evaporator comprising a coolant pump operable to draw water from a source and discharge the same to the tubes of the cooler at a rate many times in excess of the feed water requirements of the evaporators, a conduit leading from the cooler and discharging to the lowermost tubes of the condenser for flow of the coolant water progressively upwardly through the tubes of the condenser counter to the direction of flow of vapor and distillate in the condenser, a conduit tapped into the coolant water circuit of the condenser at a point in advance of the end thereof, a second conduit tapped into the coolant water circuit of the condenser at the end thereof with the flow of water through the last named first and second conduits being proportioned so that the water flowing through said last named second conduit is raised to a temperature just short of boiling, an aerator to which said last named second conduit discharges, and means including a pump for drawing water from said aerator and continuously supplying the same to the first evaporator at a rate of 75% to 100% in excess of the evaporation requirements of both evaporators.
